R. H. MICHELL.

METHOD OF CONSUMING SMOKE.

No. 399,062.

Patented Mar. 5, 1889.

INVENTOR.

Richard Henry Michell

his Attorney.

UNITED STATES PATENT OFFICE.

RICHARD HENRY MICHELL, OF REDRUTH, COUNTY OF CORNWALL,
ENGLAND.

METHOD OF CONSUMING SMOKE.

SPECIFICATION forming part of Letters Patent No. 399,062, dated March 5, 1889.

Application filed May 25, 1888. Serial No. 275,023. (No model.)

To all whom it may concern:

Be it known that I, RICHARD HENRY MICHELL, engineer, a subject of the Queen of Great Britain, residing at Redruth, in the county of Cornwall, England, have invented a new and useful Method of Consuming Smoke, of which the following is a specification.

The object of this invention is to mechanically separate the combustible from the incombustible gases generated in a furnace or other fire-place, and depends mainly upon the physical properties of the unconsumed gases themselves.

For the purposes of my invention I return the unconsumed gases back again into the same or another fire, so as to produce their complete combustion. I take them as soon as they have left the fire-place and conduct them back again by a pipe or other suitable channel, (which may be termed the "return-flue,") and reintroduce them into the fire-place at or near the door, or into such other part of the fire-place as may be found most desirable, and in such a manner as may be most likely to insure their complete combustion. The process of returning them into the fire is to go on continuously until they are consumed. The means by which this object is to be attained is a "fan" or other motor, placed in connection with the "return-flue," which is to take the unconsumed combustible gases and cause them to re-enter the fire-place and compel them to travel in such a manner as may be required for their complete combustion. The action of the said fan or other motor is to be continuous, always bringing the unconsumed combustible gases back again into the fire-place, and there completing their combustion by mixing them with the oxygen of the air supplied under the fire-place in the ordinary way in the necessary quantities to effect this result. The draft of the fire is also to be regulated by the said fan or other motor, thereby producing a brisk sharp fire or one just sufficient to consume the gases arising from it, at the option of the fireman.

For promoting the sanitary condition of towns this invention may be applied to the fire-places of dwelling-houses or streets of houses. In this case the ascending flue or

chimney must have a damper on it, or be disconnected with the fire-place, and then be connected with a rarefied smoke-drain placed in the street or elsewhere. The smoke and other gases are to be drawn out of the flue of the chimney and out of the smoke-drain by a fan or other means of producing an exhaustion, and blown into the fire-place of a boiler, gas-retort, or other furnace, to be there consumed, as before described.

The sewers should also be connected with the said smoke-drain at various intervals to take away the foul gases from them, so that they may be dealt with, as before described, in the furnace provided for the purpose, as aforesaid.

And in order that my invention may be more fully understood and carried into practice, I now proceed to describe the same with reference to the accompanying drawings, in which similar letters indicate corresponding parts.

Figure 1 is a side elevation of my invention as applied to a marine steam-boiler. Fig. 2 is a plan of the same.

The smoke arising from the fire-place is led to a fan or other exhauster, A, by means of a pipe, a, connecting in practice with the fire-place and the fan-case, and from thence led back again to any convenient part of the fire-place by the return-flue B.

It is well known that the specific gravity of the incombustible gases is greater than that of the combustible gases, and I take advantage of this fact in my invention in the following manner: When the mixed gases are led into the fan or other exhauster, A, the centrifugal force developed thereby will cause the heavier gases to arrange themselves around the periphery of the said fan or other exhauster. The return-flue B is fitted with a damper or separator, C, pivoted at D, so as to revolve in the same plane as the fan. The said separator can be so arranged as to take up two extreme positions: first, the position C', when the whole of the gases are cut off from the fire and are led up the chimney-flue E; second, the position C², in which the whole of the gases are cut off from the chimney E and are discharged under the furnace-bars.

It is well known that if the separator is in the second position, C², the constant discharge of the mixed gases into the fire-place will eventually extinguish the fire. Now, the separator C can be so regulated that it shall take up any position between these two extremes, and since, by reason of their greater weight, the incombustible gases are arranged, as before stated, around the periphery of the fan or other exhauster, it is obvious that the said separator C can be made to cut off any required quantity of the said incombustible gases, and so divide the gases thrown off from the exhauster as to lead the heavier incombustible gases from the periphery of the chimney E, and return the lighter combustible gases along the return-flue B.

It will readily be understood that if a smoke-drain were constructed in any convenient locality and provided with an exhauster fitted with a separator pivoted so as to revolve in the same plane as the exhauster, the smoke from dwelling-houses and other places would be led therein by the vacuum caused by the

revolution of the fan, and could there be separated and the combustible gases utilized in any convenient manner. 25

What I claim is—

The method herein described for consuming smoke for its utilization as fuel, which consists in mechanically separating the combustible from the incombustible gases, and varying the feeding of the lighter combustible gases to the fire, such separation being effected by the centrifugal force developed by a rotary fan or exhauster, and such variation of the feeding of the combustible gases being effected by the adjustment or manipulation of the damper, substantially as set forth. 30 35

In testimony whereof I have hereunto set my hand this 24th day of April, 1888. 40

RICHARD HENRY MICHELL.
